UNITED STATES PATENT OFFICE.

THOMAS J. BROWN, OF CRAWFORDSVILLE, IOWA.

OVERSHOE-RETAINER.

1,253,140.

Specification of Letters Patent.

Patented Jan. 8, 1918.

Application filed February 7, 1917. Serial No. 147,190.

To all whom it may concern:

Be it known that I, THOMAS J. BROWN, a citizen of the United States, residing at Crawfordsville, in the county of Washington and State of Iowa, have invented new and useful Improvements in Overshoe-Retainers, of which the following is a specification.

This invention contemplates the provision 10 of an overshoe retainer, and embodies a construction whereby the overshoe is effectively held associated with the shoe so as to prevent casual separation of these members, which frequently occurs when one 15 is forced to pass through mud, snow and the like.

More specifically stated the invention embodies a heel plate adapted to be secured within the overshoe, and provides a support 20 for a locking element designed to effectively engage the heel of the shoe, for holding the overshoe in position on the foot of the wearer.

In carrying out the invention I aim to 25 provide a construction whereby the locking element can be conveniently adjusted and held in an inactive position to facilitate putting on of the overshoe, together with means for automatically adjusting the locking element to an active position.

The nature and advantages of the invention will be better understood from the following description when read in connection with the accompanying drawing, the 35 invention residing in the construction, combination and arrangement of parts as claimed.

In the drawing forming part of this specification like numerals of reference indicate 40 similar parts in the several views and wherein:—

Figure 1 is a view showing the manner of using the invention, the overshoe being partly in section for this purpose.

Fig. 2 is a plan view of the device showing the locking element in inactive position.

Fig. 3 is a detail view of the device showing the locking element in its active position.

The device forming the subject matter of my invention preferably embodies a plate 10 shaped to conform to the configuration of the heel of the overshoe indicated generally at A, and to which the plate is adapted to be 55 secured on the inside of the overshoe in any suitable manner. The forward edge of the

plate is provided with extensions 11, the latter terminating to provide loops 12, constituting bearings for a transverse rod 13 which is mounted for partial rotation within the bearings. One end of the rod is bent 60 at right angles as at 14, while this portion of the rod is reversely bent to provide the portion 15, the latter being coiled about the rod 13 and terminating to provide a pointed 65 prong 16 disposed adjacent one extremity of the rod 13. The opposite extremity of the rod terminates to provide a prong 17 similar to the prong 16, with which it is disposed in spaced parallel relation. Coiled 70 about the rod 13 between the prongs 16 and 17 respectively is a coil spring 18, the latter being provided with an intermediate looped extension 19 which is secured to the plate in a manner to tension the spring for holding 75 the prongs 16 and 17 in an upright or active position.

In practice, the overshoe is applied to the shoe preferably in the ordinary well known manner, and just prior to the positioning 80 of the heel of the shoe proper into the heel of the overshoe, the portions 14 and 15 of the rod, which constitute a manipulating member for the latter, are depressed, thereby rotating the shaft for the purpose of 85 moving the prongs 16 and 17 forwardly of the plate 10 to an out of the way position to facilitate the application of the overshoe. During this operation, the spring 18 is placed under maximum tension. Subsequent 90 to positioning the heel of the shoe proper into the heel portion of the overshoe, the manipulating member is released, whereupon the spring 18 functions to rotate the rod 13 in an opposite direction, during 95 which operation the prongs 16 and 17 respectively embed themselves in the heel of the shoe proper, thus providing an effective connection between the shoe proper and the overshoe, with a view of preventing casual 100 separation of these parts under any condition. In this position of parts, the manipulating member defined by the portions 14 and 15 respectively of the rod 13, is arranged vertically between the shoe proper 105 and the overshoe indicated at A, and can be conveniently grasped to rotate the shaft in the proper direction to disengage the prongs 16 and 17 from the heel of the shoe proper, when it is desired to remove the 110 overshoe.

While it is believed that from the fore-

going description the nature and advantages of the invention will be readily apparent, I desire to have it understood that what is herein shown and described is merely illustrative of the preferred embodiment of the invention to which I do not limit myself, and that such changes may be resorted to when desired as fall within the scope of what is claimed.

10. What is claimed is:—

1. The combination with an overshoe, of a plate engaged therein, bearings formed at two corners of the plate, a rod journaled in said bearings, said rod terminating at one end in an upwardly extending prong, the opposite end of the rod being bent at right angles to provide a lever, said lever being reversely bent and coiled about the rod and terminating in a second prong, said prongs being disposed in spaced parallel relation,

and yieldable means operating to normally maintain said prongs in a position to engage the heel of the shoe.

2. The combination with an overshoe, of a plate engaged therein, bearings formed on said plate, a rod journaled in said bearings, a prong formed at one end of said rod, the opposite end of said rod being bent at right angles to provide an operating lever for the rod, said lever being reversely bent and coiled about the rod, terminating in a prong disposed in spaced parallelism with the first mentioned prong, and a coiled spring encircling said rod and operating to normally maintain the prongs in heel engaging position, said spring having an intermediate loop engaging beneath said plate as described.

In testimony whereof I affix my signature.

THOMAS J. BROWN.
